UNITED STATES PATENT OFFICE

CHARLES D. KARR, OF HOLLAND, MICHIGAN

SPRING ASSEMBLY

Application filed February 15, 1930. Serial No. 428,594.

This invention relates to spring assemblies and more particularly to assemblies in which a plurality of spiral springs are employed.

The principal object of the invention is the provision of new and improved means for connecting the spirals of a spring assembly together.

Another object of the invention is the provision of a new and improved spring assembly composed of a plurality of spiral springs having overlapping portions together with novel means for holding said portions in lapped position.

A further object of the invention is the provision of a new and improved spring assembly that is inexpensive to manufacture, simple in construction and efficient in use.

Other and further objects and advantages of the invention will appear from the following description taken in connection with the accompanying drawing, in which

Fig. 1 is a plan view of a portion of a spring assembly embodying the invention; and

Fig. 2 is a section on line 2-2 of Fig. 1.

In the construction of spring assemblies for use in box springs, mattresses, cushions and the like it is desirable that the springs be connected together in such a manner that they will have flexibility of movement in all directions and be noiseless in use and at the same time be provided with means for preventing rotation of the individual springs.

These functions are performed by the arrangement of spring assembly that will now be described.

Referring now to the drawing, the spring assembly comprises a plurality of spiral springs 11 and 12 preferably arranged in rows both longitudinally and transversely of the assembly. Each of the springs is provided with a plurality of distorted portions in their terminal coils that are adapted to be connected together and the springs held in assembled relation by a plurality of clip members.

In the form of the device selected to illustrate one embodiment of the invention the spirals 11 are provided with outwardly extending loops 13 in the terminal coils 14 of

said springs. The loops 13 preferably extend radially outwardly and are substantially in the planes of said coils. The terminal coils 15 of the springs 12 are provided with corresponding loops 16 which extend at an angle to the planes of the coils.

For the purpose of description the portions of the structure shown in Fig. 2 toward the top of the sheet will be referred to as the upper portion of the coil. The loops or offsets 16 extend upwardly as shown in Fig. 2 and at one side of said loop is a depression 17 extending below the plane of the terminal coil and a depression 18 at the other side of said loop.

In assembling the device the spiral springs 11 and 12 are arranged alternately with the loops 13 lapped over the loops 16 of the springs 12, the parts being so constructed that the sides of the loops 13 will ride down in the depressions 17 and 18 when the springs are rocked. The loops are held in lapped position by any suitable means. In the form of the construction shown, clips 19 are employed for this purpose. These clips are formed from lengths of wire doubled back on themselves to form the loop portion 21. The loop portion 21 engages the loops 13 and 16 by passing upwardly beneath the loop 16 and between the two loops and over the loop 13.

The ends of the clip are bent to form retaining members 22 and 23 that are adapted to be snapped over the terminal coil 14 at each side of the loop 13 after the loop 21 has been placed in position. By means of this arrangement, the connection formed by the clip and cooperating distorted portions of the terminal coils, will permit a hinged pivotal movement of the connected springs, and at the same time retain the parts in such relation that there will be no clicking of those parts during use.

By means of this arrangement, the connection between the coils will permit the necessary flexing of the coils without the objectionable clicking or other metallic sounds so evident in the use of spring assemblies of the usual or well known construction.

The terminal coils of each spring may be

duplicates whereby two types of spirals will be necessary, one provided with horizontal loops in its terminal coils, and the other with vertical loops in its terminal coils, but in practice it is preferable to have the terminal coil at one end of the spring provided with the distorted portions or horizontal loops 13 and the other terminal coil provided with the vertically arranged loops 16 whereby the 10 spirals will all be alike, it being only necessary to reverse each alternate spring in assembling the springs.

While the connections described are shown as being between the terminal coils of spiral 15 springs, it is understood that this same arrangement may be used where two or more curved or circular wire units are to be connected together in such a manner as to provide a limited universal movement of the 20 units with noiseless operation of the same.

I claim as my invention:

1. In a spring assembly, a plurality of spiral springs arranged in rows, the terminal coil of one of said springs being provided with a radially extending loop and the cooperating adjacent spring being provided with an upstanding loop having a depression at each side thereof, the radially extending loop engaging over the upstanding 30 loop and a connecting element for holding said loops in assembled relation whereby said springs are pivotally and rockably connected together.

2. In a spring assembly, a plurality of 35 spiral springs, each having a terminal coil provided with a distorted portion, the distorted portion of one coil being in the form of a loop arranged at an angle to the plane of said coil and having depressions at each 40 side thereof, the cooperating distorted portion of the adjacent coil being in the form of a loop extending about said first-named loop and engaging in said depressions, and means for holding said loops of adjacent

45

coils in engagement with each other, whereby said coils will be hingedly and rockably connected together.

3. In a spring assembly, a plurality of spiral springs, each having a terminal coil provided with a distorted portion, the distorted portion of one coil being in the form of a loop arranged at an angle to the plane of said coil and having depressions at each side thereof, the cooperating distorted portion of the adjacent coil being in the form of a loop extending about said first-named loop and engaging in said depressions, and a clip formed of wire doubled on itself to form a loop extending beneath said first-named loop and over the last-named loop and having its ends attached to one of said coils. 75

4. A spiral spring for use in a cushion, mattress or the like, comprising a spiral body portion having one of its terminal coils provided with a plurality of distorted portions comprising loops extending laterally from said coil and its other terminal coil provided with a plurality of distorted portions comprising an upwardly extending loop having a depression at each side thereof, said depressions extending below the plane of the corresponding terminal coil. 85

5. In a spring assembly, a plurality of 90 spiral springs, the terminal turn of each spring being provided with a distortion in the form of a loop, the distortion of one spring engaging that of an adjacent spring, the loop of one of said springs being in a 100 substantially vertical plane and the other loop being in the plane of its corresponding terminal turn and embracing the outer end of the first named loop and means for holding said loops in engagement whereby said loops will be connected together and said 105 terminal turns may swing and rock in vertical planes relative to each other. 95
